(57) CLAIM

An ornamental design for an adapter for use with memory card, as shown and described.

DESCRIPTION

FIG. 1 is a front elevational view of an adapter for use with memory card, showing my new design;

FIG. 2 is a top plan view thereof;

FIG. 3 is a bottom plan view thereof;

FIG. 4 is a rear elevational view thereof;

FIG. 5 is a right side elevational view thereof;

FIG. 6 is a left side elevational view thereof;

FIG. 7 is a front, bottom and right side perspective view thereof;

FIG. 8 is a rear, top and right side perspective view thereof; and,

FIG. 9 is a front, bottom, and right side perspective view of the adapter together with a board, an electrical connector mounted thereon, and a memory card in a state where the memory card is not inserted in the adapter.

The broken line showing of the environment is for illustrative purposes only and forms no part of the claimed design.
